United States Patent Office

Des. 219,722
Patented Jan. 12, 1971

219,722

TIRE

Rush M. Johnson, Jr., Wadsworth, Ohio, assignor to The
B. F. Goodrich Company, New York, N.Y., a corpora-
tion of New York

Filed Oct. 9, 1969, Ser. No. 19,487

Term of patent 14 years

Int. Cl. D12—14

U.S. Cl. D90—20

The figure is a perspective view of a tire showing my new design.

It is to be understood that the tread pattern as shown continues throughout the circumference of the tire.

I claim:

The ornamental design for a tire, substantially as shown and described.
